UNITED STATES PATENT OFFICE.

JOSEPH F. O'REILLY, OF OAKLAND, CALIFORNIA.

DESIGN FOR A BOLT.

56,304.

Specification for Design. Patented Sept. 14, 1920.

Application filed January 13, 1920. Serial No. 351,258. Term of patent 3½ years.

To all whom it may concern:

Be it known that I, JOSEPH F. O'REILLY, a citizen of the United States, and a resident of Oakland, county of Alameda, State of California, have invented a new, original, and ornamental Design for a Bolt, of which the following is a specification, reference being had to the accompanying drawing, forming part thereof.

The distinguishing features of my design include a main shank provided with a head extending laterally from the shank, and a

toe extending laterally from opposite sides of the shank.

The drawing is a perspective view of my bolt.

I claim:

The ornamental design for a bolt, substantially as shown and described.

JOSEPH F. O'REILLY.
